The following table gives some other examples prepared in an analogous manner to Example 1.

the fibre and does not migrate to the cold parts of the apparatus.

Example	First constituent	Intermediate constituent	Final constituent	Shade
2	Aniline	Aniline	N,N-dicyanoethyl aniline	Reddish-yellow.
3	4-chloro-2-methylaminobenzene	Meta-anisidine	do	Yellow-orange.
4	Ortho-bromaniline	Meta-toluidine	do	Do.
5	Para-anisidine	Aniline	do	Do.
6	Meta-chloraniline	Meta-anisidine	do	Do.
7	Aniline	Alpha naphthylamine	N,N-dicyanoethyl-meta-toluidine	Brownish-red.
8	2,4-dichloroaniline	Meta-anisidine	do	Orange.
9	Aniline	Aminohydroquinone dimethylether	do	Brownish-red.
10	2,5-dichloroaniline	Meta-toluidine	do	Orange.
11	Aniline	Meta-chloraniline	do	Yellow-orange.
12	Para-chloraniline	Para-cresidine	do	Red-orange.
13	2,4-xylidine	Meta-toluidine	do	Do.
14	Ortho-toluidine	Ortho-toluidine	do	Orange-red.
15	Aniline	Aniline	N,N-dicyanoethyl meta-anisidine	Red-orange.
16	Ortho-chloraniline	Meta-chloraniline	do	Orange.
17	Meta-toluidine	Meta-anisidine	do	Red-orange.
18	Aniline	Aniline	N,N-dicyanoethyl-meta-chloraniline	Reddish-yellow.
19	Ortho-chloraniline	Meta-anisidine	do	Orange.
20	Ortho-toluidine	Ortho-toluidine	do	Yellow-orange.

EXAMPLE 21

A printing paste of the following composition is prepared:

	Parts
Dyestuff of Example 15	10
Sodium dinaphthylmethane-disulphonate	14
Ethylene glycol monoethyl ether	50
Water	300
Aqueous solution of sodium chlorate containing 300 g. per litre	30
Starch tragacanth thickener	600

This paste is applied on a grooved roller to a fabric of polyester fibres, previously desized at 45° C. by alkaline washing. The colour is fixed by steaming under pressure at 130–140° C. The fabric is rinsed and treated in the hot with an alkaline reducing bath containing 1 to 2 g. per litre of a nonylphenol-ethylene oxide condensate. The fabric is coloured a red-orange shade of excellent fastness; the reserved parts being white.

EXAMPLE 22

A foularding bath of the following composition is prepared:

	Parts
Dyestuff of Example 6	30
Sodium dinaphthylmethane-disulphonate	7
Starch tragacanth thickener	5
Water	58

A strip of polyester fabric is foularded several times in this dispersion and heat-fixed for one minute at 200° C. Since the dyestuff is fast to sublimation, it remains on

We claim:

1. Disazo dyestuffs having one of the formulae:

in which U and V each represent a hydrogen or chlorine atom, V is fixed on the position 4 or 5. X represents a hydrogen atom or a methyl or methoxy group, and Y and Z each represent a hydrogen or chlorine atom or a methyl or methoxy group.

2. Disazo dyestuffs according to claim 1 in which U and V are hydrogen atoms.

IN THE UNITED STATES PATENT OFFICE

CERTIFICATE OF CORRECTION

Patent No. 3,479,322

Dated Nov. 18, 1969

A. H. Peterson

It is certified that error appears in the above-identified patent and that said Letters Patent are hereby corrected as shown below:

In the patent, Col. 3, line 36 -- "marco" should read --macro--

Col. 4, line 2 -- "monotmor" should read --montmc

Col. 4, line 35 -- "primer" should read --trimer--
